DESIGN FOR A FLASHLIGHT ATTACHMENT FOR A CAMERA

Morris Schwartz, New York, and William Castedello, Huntington, N. Y.

Application May 9, 1940, Serial No. 92,236

Term of patent 14 years

To all whom it may concern:

Be it known that we, Morris Schwartz and William Castedello, citizens of the United States, residing respectively in New York city, in the county of New York and State of New York, and Huntington, in the county of Suffolk and State of New York, have invented a new, original, and ornamental Design for a Flashlight Attachment for a Camera, of which the following is a specification, reference being had to the accompanying drawing, forming part thereof.

Fig. 1 is a front elevational view of a flashlight attachment for a camera, showing our new design.

Fig. 2 is a side elevational view thereof, and Fig. 3 is a rear elevational view thereof.

The characterizing features of my design reside in the specific bulb supporting and releasing member associated with a reflector as shown.

We claim:

The ornamental design for a flashlight attachment for a camera, substantially as shown and described.

MORRIS SCHWARTZ.
WILLIAM CASTEDELLO.
